Inventor:

Clarence W. Taylor,

UNITED STATES PATENT OFFICE.

CLARENCE W. TAYLOR, OF OAK PARK, ILLINOIS.

COMB AND COMB-CLEANER COMBINED.

No. 820,533.

Specification of Letters Patent.

Patented May 15, 1906.

Application filed August 19, 1905. Serial No. 274,948.

To all whom it may concern:

Be it known that I, CLARENCE W. TAYLOR, a citizen of the United States, residing at Oak Park, in the county of Cook and State of Illinois, have invented certain new and useful Improvements in a Comb and Comb-Cleaner Combined, of which the following is a specification.

My invention relates to improvements in combs and comb-cleaners combined, and has for its object, first, to provide a comb and comb-cleaner combined which shall be simple in construction, comparatively inexpensive to manufacture, and sanitary in use, and, second, to produce an article of the class adapted to be washed or cleansed without removing the cleaner from the comb.

With these and other objects in view my invention consists of the novel form and the means for removably securing the cleaner to the comb and the combination and arrangement of parts hereinafter more specifically described, illustrated in the drawings, and particularly pointed out in the claims hereunto appended.

In describing the invention in detail reference is had to the accompanying drawings, forming a part of this specification, wherein like numerals of reference indicate corresponding parts throughout the several views, and in which—

Figure 1 is a side view of my comb and comb-cleaner combined, showing the cleaner in normal position and showing the side of the comb on which the main portion of the cleaner is mounted. Fig. 2 is a view of the comb and cleaner, showing the side opposite from the one on which the main portion of the cleaner is mounted, but with the cleaner in a position intermediate the upper and lower ends of the teeth of the comb. Fig. 3 is a view of the cleaner as it comes from the die. Fig. 4 is a top plan view of the cleaner formed to be mounted on the comb. Fig. 5 is a section on line 5 5 of Fig. 1.

Referring to the drawings by reference numerals, 6 denotes the comb, which is provided with depressions or recesses 7 7 near the ends of the comb.

Reference character 8 indicates the comb-cleaner. As shown in Fig. 3, the cleaner is made of one piece of material and by the use of a die. The projections 9 on the cleaner are formed substantially at right angles with the body portion, and these projections are disposed between the teeth of the comb when

assembled together. The ends 10 10 in Fig. 3 are formed substantially at right angles to the body of the cleaner and preferably may be inserted between the end and second 60 teeth and then bent to bear upon the surface near the ends of the comb, or the ends may be formed as shown in Fig. 4 and then mounted upon the comb. The raised portions 11 11, Figs. 2 and 4, or their equivalents on the 65 spring ends 10 10, may be of any desired form. I have shown a round form of depression or recess 7 7 and a correspondingly round form 11 11 for engagement with such depressions.

The cleaner may be made of any suitable material. Aluminium with an alloy will give good results.

For sanitary reasons, preferably, the cleaner is small and the body portion embraces only 75 one side of the comb. It may be washed or cleaned without being entirely disengaged from the comb.

In a comb of any suitable material I provide depressions in at least one surface of the 80 comb near its ends and form the ends of the cleaner suitably for spring-pressure against such surface and for removable engagement therewith.

In assembling the comb and cleaner, if the 85 cleaner is first formed as in Fig. 4 it will be apparent the spring ends of the cleaner may be lifted a trifle and the cleaner pushed up the end teeth to its normal position.

In operation when it is desired to clean the 90 comb the cleaner may be pushed downward with sufficient force to disengage the raised portions 11 11 from the depressions 7 7 to the ends of the comb-teeth and the accumulation removed.

I reserve the right to make such changes, variations, and modifications as come properly within the protection prayed.

Having thus fully described my invention, what I claim as new, and desire to secure by 100 Letters Patent, is—

1. The combination with a comb having a depression in one surface near each end thereof, of a cleaner the major portion of its length embracing only one side of the comb and 105 having projections disposed between the teeth of the comb, the end portions of said cleaner being suitably formed to bear only upon the opposite side of the comb and removably engage said depressions to secure 110 the cleaner to the comb.

2. The combination with a comb having a

depression near each end thereof, of a cleaner
the major portion of its length embracing
only one side of the comb and having projec-
tions disposed between the teeth of the comb
5 and having its end portions adapted to pass
between the teeth of the comb near the ends
thereof and bear only upon the opposite side
of the comb and having its ends suitably

formed for spring engagement with said de-
pressions to secure the cleaner to the comb. 10

In testimony whereof I affix my signature
in presence of two witnesses.

CLARENCE W. TAYLOR.
